United States Patent Office

Des. 220,083
Patented Mar. 9, 1971

220,083

COMBINED BOTTLE AND COVER THEREFOR

James Tucker, Chicago, Ill., assignor to The Gillette
Company, Boston, Mass.

Filed Sept. 24, 1969, Ser. No. 19,280

Term of patent 14 years

Int. Cl. D9—01

U.S. Cl. D9—144

FIG. 3

FIG. 1

FIG. 2

FIG. 1 is an elevational view of a combined bottle and cover therefor showing my new design;

FIG. 2 is an elevational view looking from the right of FIG. 1; and

FIG. 3 is a top plan view thereof.

I claim:

The ornamental design for a combined bottle and cover therefor, as shown.
